[54] VEHICLE MOTOR MOUNTING
FACILITATING MOTOR INSTALLATION[75] Inventor: Robert D. Higgins, Highland
Heights, Ohio[73] Assignee: Towmotor Corporation, Mentor,
Ohio

[21] Appl. No.: 904,087

[22] Filed: May 8, 1978

[51] Int. Cl.² B60K 5/02

[52] U.S. Cl. 180/299

[57] ABSTRACT

A motor mounting assembly is separable into two portions between the frame and the motor enabling one

portion of the mounting assembly to remain resiliently connected to the vehicle frame while the other portion is removed with the motor. Reinstallation of the motor is greatly simplified as the separable portions of the mounting assembly can readily be repositioned and reconnected without the misalignment problems encountered during installation of motors using conventional mounts which must be engaged at the vehicle frame.
